UNITED STATES PATENT OFFICE.

JOHN L. LONGSTRETH, OF PHILADELPHIA, PENNSYLVANIA, ASSIGNOR OF THREE-FOURTHS TO HOWARD B. FRENCH, OF SAME PLACE, AND SAMUEL H. FRENCH AND WILLIAM A. FRENCH, OF HADDON TOWNSHIP, CAMDEN COUNTY, NEW JERSEY.

FEED-WATER APPARATUS.

SPECIFICATION forming part of Letters Patent No. 328,325, dated October 13, 1885.

Application filed July 23, 1885. Serial No. 172,382. (No model.)

To all whom it may concern:

Be it known that I, JOHN L. LONGSTRETH, a citizen of the United States, residing at Philadelphia, Pennsylvania, have invented certain 5 Improvements in Exhaust-Steam Feed-Water Apparatus, of which the following is a specification.

The object of my invention is to prevent the escape of any of the water of condensation with 10 the exhaust-steam from the discharge-pipe of the engine and to return said water of condensation and part of the exhaust-steam, if desired, to the boiler, either alone or in connection with the cold-water supply.

15 In the accompanying drawings, Figure 1 is a side view of a steam-engine with a feed-water heater and circulating apparatus constructed in accordance with my invention, and Fig. 2 a plan view of the heater and circulating apparatus. Figs. 3 and 4 represent modifications of my invention.

A represents the cylinder of a steam-engine, and B the exhaust-pipe of the same, the latter communicating with the casing D, in which is arranged the coil of pipes for the circulation of the feed-water, the outlet end a of this coil being in communication with the boiler, and the inlet end b of the coil communicating with the pump F, the plunger of which is in the 25 present instance operated from the cross-head of the engine by means of connecting rods and levers, which, however, form no essential part of my invention, as the pump may be operated in any desired manner without departing from the main feature of the invention.

30 The exhaust-steam escapes from the casing D through the pipe G, which communicates with the discharge-branch H, and has a return-bend, I, so that the water of condensation will not be driven out through the pipe H, but will 35 return through this bend, which communicates through a pipe, d, with the pump F. The pipe d has a check-valve, f, and a stop-valve, g, the check-valve serving to prevent back-flow through the pipe d, and the stop-valve 40 serving to regulate or cut off the forward flow, as circumstances may suggest. With the pipe

d communicates a pipe, h, which derives a supply of water from any adjacent reservoir or hydrant, and is provided with a stop-valve, 50 m, whereby the flow through the pipe may be regulated or cut off, as desired.

By means of this circulating system back-pressure on the piston of the engine is prevented or a partial vacuum behind the piston 55 produced, and the water of condensation is returned to the pump F and forced through the pipe b into the heating-coil in the casing D, and thence to the boiler as feed-water, any desired amount of cold water being admitted to 60 the pipe d from the pipe h to maintain the necessary volume. A portion of the exhaust-steam may be drawn into the pump with the water of condensation, this exhaust-steam passing with the water of condensation through 65 the heater to the boiler, or being condensed or partly condensed by the jet from the pipe h when the valve in the latter is opened, so that the initial temperature of the feed-water entering the coil in the casing D is such that 70 its temperature on leaving the coil will closely approach that of the exhaust-steam.

If desired, the water of condensation and exhaust-steam may be controlled by a separate pump and returned to the boiler independently of the feed passing through the heater, as shown in Fig. 3, or the heater may be dispensed with, the water of condensation, exhaust-steam, and water from the pipe h being forced by the pump F directly into the 80 boiler. (See Fig. 4.)

I am aware that it is not new to pump feed-water through a casing containing tubes through which a portion of the exhaust-steam is caused to pass for the purpose of heating 85 the feed-water; hence this idea broadly I do not claim; but

I claim as my invention—

1. The combination of the exhaust-pipe of the engine, the discharge-branch, and the feed-pump with the pipe G, communicating with said discharge-branch and having a return-bend communicating with the feed-pump, as specified.

2. The combination of the feed-water heater and the exhaust-pipe communicating therewith with the discharge-branch, the feed-pump, and the outlet-pipe G, communicating with the heater and discharge-branch and having a return-bend communicating with the feed-pump, as set forth.
3. The combination of the exhaust-pipe, discharge-branch, and feed-pump with the outlet-pipe communicating with the discharge-branch and having a return-bend communicating with the feed-pump and the cold-water supply-pipe h, as specified.

4. The combination of the exhaust-pipe, discharge-branch, and feed-pump with the outlet-pipe communicating with the discharge-branch and having a return-bend, I, and a pipe, d, communicating with the feed-pump and having a check-valve, f, as specified.

In testimony whereof I have signed my name to this specification in the presence of two subscribing witnesses.

JOHN L. LONGSTRETH.
